FENCE POST

William J. Kibler, Tonawanda, N. Y., assignor
to Buffalo Steel Company, Tonawanda, N. Y.,
a corporation of New York

Application January 2, 1932, Serial No. 584,425

8 Claims. (Cl. 256—57)

This invention relates to a fence post of the type which is adapted to be driven into the ground and employed to support the horizontal strands of a wire fence.

5 The principal object of the invention is to provide a strong, durable fence post, the main bar of which may be inexpensively manufactured by the hot rolled process and to which may be conveniently attached, at any desired height, the 10 horizontal strands of a wire fence, the latter being readily detachable at any subsequent time without injury or alteration to the main bar of the fence post.

Numerous other objects of the invention and 15 practical solutions thereof are disclosed in detail in the herein patent specification wherein:

In the accompanying drawing:

Figure 1 is a diminutive, fragmentary side elevation of the fence post with a portion of a wire 20 fence secured thereto.

Figure 2 is a horizontal, transverse section thereof taken on line 2—2, Fig. 1.

Figure 3 is a top plan of one of the wire clips in its original form, that is prior to being applied 25 to the fence post proper.

Figure 4 is a fragmentary front elevation of a modified method of securing the wire fence to the fence post.

In the following description, similar characters 30 of reference indicate like parts of the several figures of the drawing.

My invention may be embodied in various forms and in fence posts of different constructions, and the present application is therefore to be regarded 35 merely as one organization which satisfactorily carries out the invention in practice. As here shown, the same is constructed as follows:

The main body of the fence post consists of a 40 hot rolled T bar 10 comprising chiefly the front longitudinal face plate 11 which is integrally connected at its central portion with a rearwardly and longitudinally extending web or flange 12 formed perpendicularly of said face plate 11. At the junction of said face plate 11 and flange 45 12 is provided an integral, square-shouldered fillet 13 whose flat face is disposed perpendicularly of said face plate. The reasons for this arrangement of fillet will be hereinafter stated. The lower end of the face plate 11 is symmetrically bevelled on opposite sides at 14 so as, in effect, to provide a point at the lower end of the fence post, thereby enabling the same to be driven into the ground 15 without requiring excessively heavy blows for the driving operation.

50 In the fabrication of the hot rolled T bar 10,

which constitutes the chief element of the fence post, the outer and opposite longitudinal edges of its face plate 11 are transversely bent (or rolled directly) so as to project outwardly and rearwardly to form the curvilinear edge portions 20 and 20a. The extreme parts of said edge portions are serrated, i. e., provided with rows of uniformly spaced lugs 21 and 21a respectively, the one row of lugs 21 being staggered relatively to the row of lugs 21a. Each individual lug in each row of lugs is preferably (though not necessarily) of symmetrical shape and has its upper and lower ends bevelled at 22 and 22a respectively.

This improved fence post is adapted to support either a barbed wire or a woven wire or any other kind of a wire fence. Fig. 1 illustrates a pair of horizontal strands 23, 23a of a wire fence in which each strand is independent of the others arranged in the manner in which ordinary barbed wire fencing is usually installed. In such a case 20 it is customary practice to first put a tension on each of said strands 23, 23a prior to fastening the same to the fence post, and it will therefore be assumed that such a tension has been applied and that, while being applied, each strand is secured in place by a bent wire clip 24. This clip, prior to being applied to the fence post, has the form shown in Fig. 3 and comprises the central or securing portion 25, the curled retaining finger 26 and the securing arm 27.

In applying this wire clip to the fence post, the particular strand 23 or 23a (which said clip is to support) is moved up or down to its proper vertical position, and then either the retaining finger 26 or the securing arm 27 of a clip 24 passed around the curvilinear edge portion 20 or 20a of the T bar 10 at a point where the bevel 22 of one of the lugs 21 or 21a is positioned just above said wire. For instance, the upper wire fence strand 23a is illustrated as just below the bevel 22 of one of the lugs 21a located on the "right" side of the fence post, in which case said strand 23a is supported by a wire clip engaging with the curvilinear edge portion 20a just above the bevel 22 of the particular lug 21a which is immediately 40 adjacent. The conditions in regard to the other wire fence strand 23 are different. In this case said strand 23 is located just below the bevel 22 of one of the lugs 21 located on the "left" side of the fence post, and, consequently, either the retaining finger 26 or the securing arm 27 of this clip is passed around the curvilinear edge portion 20 just above the bevel 22 of the particular lug 21 which is immediately adjacent. Whether 45 the finger 26 or the arm 27 of any particular clip 50

- is to be engaged with its companion lug is not material, it being manifestly undesirable to expect the person, who is putting up the fence, to follow an unnecessarily complicated procedure.
- 5 In the case of the lower clip 24 illustrated in Figs. 1 and 2, it is the securing arm 27 which is shown as having been passed around the curvilinear portion 20 of the fence post just above one of the "left" lugs 21. In all cases, however, it is the retaining-finger 26 which is first placed in position around the one side of the fence post, after which the securing arm 27 of said clip is swung around into the position illustrated in Figs. 1 and 2. After said securing arm has been swung into position, its outer end is hammered over or otherwise bent to form the locking finger 30 (see Fig. 2) which is curled around the rear edge of the flange 12 and thereby locks both its companion strand 23 or 23a and its clip 24 to the fence post.
- 20 It is desirable that none of the strands (23 or 23a) of the wire fence be subjected to forces which would cause any of them to be sharply bent, inasmuch as such a condition would cause excessive local stresses and hence would weaken the strand as a whole. It is obvious that the strand cannot be kinked while being fastened to the fence post, because the pressure exerted by said clip against its companion strand is backed up by the broad flat outer surface of the face plate 11. Furthermore, no kink in the strand can be caused, after the fence has been set up, by a horizontal rearward strain against said strand by reason of cattle brushing heavily against it or for any other similar reason. This is because of the fact that the longitudinal edges of the face plate 11 do not end abruptly, but merge, tangentially, into the curvilinear edge portions 20 and 20a. In addition to this these curvilinear edge portions, extending somewhat rearwardly as they do, enable the lugs 21, 21a at their outer rear extremities, to support the wire clips 24 sufficiently close to the center of gravity of said clips as to prevent any undue dropping of the rear end of the securing arm 27 which otherwise would occur and would tend to loosen the clip and cause undue strains thereon when its companion strand was subjected to a succession of horizontal, forwardly directed forces.
- 30 It is obvious that greater strength is obtained by the use of a fillet between the face plate 11 and the flange 12. However, if an ordinary, quarter-circle fillet were used, the lateral guiding of the T bar 10 through the rotating rolls during the hot rolling process, would be dependent upon the flange 12 at some distance from the face plate. Such a procedure would be apt to result in wavy T bars, and it is for this reason that the square shouldered fillet 13 is employed, its flat face being longitudinal and perpendicular to the face plate and thus capable of firmly guiding the T bar through the rolls during the hot rolling process.
- 35 When it is inconvenient to subject the strands 23, 23a to a longitudinal or "stretching" pressure prior to their being clipped to the fence post, the clips themselves may be used to "tighten up" the individual strands, as shown in Fig. 4. In this case the clip 24 is pressed firmly rearwardly while the locking finger 30 of the securing arm 27 is being hammered over. Both this pressure and also the rearward pressure caused by this bending of said locking finger 30 around the rear edge of the flange 12 causes a slight S shaped twist 31 in the companion strand 23b of the wire fence, thus contracting the same longitudinally and, to some

extent at least, taking up any sag that may have been existing at the time. This action results because the securing portion 25 of the wire clip 24 is disposed curvilinearly relatively to the strand 23b.

It will be seen on the whole that the herein improved fence post is inexpensive to manufacture inasmuch as all of its constituent parts are made of rolled, drawn or swaged metal and that, despite its low cost, it is capable of easily having applied thereto the horizontal strands of a wire fence in such manner that the exact, desired, vertical spacing of said strands may be obtained. If it later becomes necessary to dismantle the fence it is only necessary to knock off the clips 24 and pull the fence post proper out of the ground without having in any way altered or injured the latter, as would be the case if, for instance, the clips 24 were made, in effect, integral with said post or bar 10. It is obvious that said post or bar 10 is of rugged and durable design and that the whole construction is such as to avoid any sharp bending of the wire strands 23, 23a, either while being installed or in use thereafter. In addition to this, the arrangement of the curvilinear edge portions 20 prevents undue sagging of the rear part of the clips 24 with its consequent imposing of heavy "toggle-action" distortion strains.

I claim:

1. A fence post comprising a face plate provided on its edge with supporting lugs having bevelled edges; and a clip adapted to engage with one of said lugs and adapted to secure one of the strands of a wire fence to said face plate.
2. A fence post comprising a face plate having a curvilinear, projecting edge adapted to make substantially tangential contact with a strand of wire fence; lugs arranged on the edge of said face plate; and a clip adapted to engage with one of said lugs and adapted to secure said strand to said face plate.
3. A fence post comprising a rolled face plate having its opposite longitudinal edges projecting curvilinearly rearwardly and adapted to make substantially tangential contact with a strand of wire fence; lugs arranged on the edge of said face plate; and a clip adapted to engage with one of said lugs and to secure said strand to said face plate.
4. A fence post comprising a rolled face plate having its opposite longitudinal edges projecting curvilinearly rearwardly and provided with supporting lugs having bevelled ends; and a clip adapted to engage with one of said lugs and adapted to secure one of the strands of a wire fence to said face plate.
5. A fence post comprising a face plate having its opposite longitudinal edges extending curvilinearly backward and provided with outwardly projecting lugs which are staggered relatively to each other; and a clip adapted to engage with any desired one of said lugs and to secure one of the strands of a wire fence to said face plate.
6. A fence post comprising a rolled face plate provided on its opposite edges with lugs which are formed to have bevelled ends and which are staggered relatively to each other; and a clip adapted to engage with one of said lugs and to secure one of the strands of a wire fence to said face plate.
7. A fence post comprising a face plate provided on its opposite longitudinal edges with lugs which are staggered relatively to each other in

such manner that the top of any one lug on one side of said face is opposite the bottom of a lug on the other side of said face plate.

8. A fence post comprising a rolled face plate provided on its edge with a row of lugs; a rolled flange extending rearwardly and integrally from the rear face of said face plate and having a

square shouldered fillet whose flat face is disposed perpendicularly of said face plate; and a clip adapted to engage with one of said lugs and to secure one of the strands of a wire fence to said face plate.

WILLIAM J. KIBLER.
